UNITED STATES PATENT OFFICE.

ELIZUR E. CLARKE, OF NEW HAVEN, CONNECTICUT.

CONCRETE WALL.

Specification of Letters Patent No. 27,970, dated April 24, 1860.

To all whom it may concern:

Be it known that I, ELIZUR E. CLARKE, of New Haven, in the county of New Haven and State of Connecticut, have invented cer-
5 tain Improvements in Concrete Walls, the construction and operation of which I have described in the following specification and illustrated in its accompanying drawings with sufficient clearness to enable competent
10 and skilful workmen in the arts to which it pertains or is most nearly allied to make and use my invention.

My said invention consists in, First, making the wall in two parts connected by isolated binders in such a manner as not to interfere with the free circulation of air between the inner and outer portions of the wall, as hereinafter more fully set forth; second, in the combination with the parts
20 of the wall made as described of binders made of vitreous blocks or other non-conductors of moisture as described, by which the absorption of moisture by the inner from the outer portion of the wall is prevented.

25 The accompanying drawings illustrate the invention as follows:

Figure 1 is a horizontal section of a wall which embodies my improvements. Fig. 2 is a longitudinal vertical section taken
30 through the binders. Fig. 3 is a vertical transverse section. Fig. 4 is a plan of one form of binder.

1 is the outer portion, and 2 is the inner portion of the wall. These parts of the wall
35 are made separate so as to give an open space between them, and by exposing more surface to the circulation of the atmosphere to allow the air to have a better action in hardening the wall. These parts 1 and 2
40 of the wall are connected by binders 3 as shown. The sides of the flues will also connect them at that point.

4 is a flue made in the usual form.

The wall is hollow entirely from top to
45 bottom, or at least nearly to each extremity. The joists extend through the inner and nearly through the outer portion of the wall, and are properly secured to it by anchor irons in a manner well known to every competent builder. The binders 3 are vitrified
50 blocks or bricks, or other material which is a non-conductor of moisture. These binders may be plain in the form of a common brick, or they may be dovetailed as shown
55 in Fig. 4. They are laid in as the walls are carried up, and the concrete attaching itself

firmly, they form a firm and substantial connection between the inner and outer parts of the wall. The binders may be made of stone or common brick if considered desirable.

A concrete wall constructed in this manner hardens more readily and perfectly than if its whole thickness were made in one solid wall as is usually the case, and the
65 wall is for this reason and by this means rendered much more durable. The insertion of ventilators from each room through the inner section of the wall also very greatly facilitates this object while it at the same
70 time serves the purpose of ventilation. The natural hardening process of calcareous cements, that of absorption of carbonic acid from the atmosphere, is thus made available upon the inner as well as the outer surfaces.
75 The formation of these walls is accomplished by laying both parts of the wall at the same time in appropriate boxes with a removable core placed in a central or nearly central position to form an opening
80 between the walls as described. The core is raised up from stage to stage as the work progresses, and is supported at each stage by the binders as shown in Fig. 3, the core being indicated by 5. Various forms of construction of this core may be employed to suit the convenience of the builder. A detailed description of these forms may perhaps belong more properly to a description
85 of the apparatus, and will be found in the specification of my apparatus for constructing concrete walls, filed in the Patent Office at the time of making this application for a patent.

By connecting the parts of the wall with
95 vitreous blocks or other non-conductors of moisture, the absorption of the moisture of one wall from the other is entirely prevented, and the interior atmosphere is thus rendered more dry and wholesome in moist
100 weather. These blocks may be vitrified bricks, or common bricks glazed so as to be impervious to moisture, or any other non-conductor of moisture desired may be used that is otherwise suitable for the purpose.
105 A good, serviceable wall may thus be made at a much less cost than by the ordinary modes of building of bricks or stone. The binders also operate much more perfectly than they could do in a wall made of brick
110 or stone, as in the construction I have described said binders are not and cannot be

broken by inequalities in the wall in which they are laid, for the whole space is accurately filled by the concrete around them, and the concrete will attach itself much 5 more firmly to them than would be the case with ordinary mortar in the common process of laying bricks or stone.

Having thus fully described my said invention, I claim—

- 10 1. A hollow concrete wall made as described by coring out a space between the inner and outer portions and connecting the parts with isolated binders as described, the combination of the isolated binders with the
- 15 parts of the wall as shown forming the necessary connection, while at the same time it

does not interfere with the circulation, but allows both lateral and vertical circulation except so far as the former is obstructed by the flues which pass upward through 20 the wall, the whole being constructed and operating substantially as set forth.

2. The combination with a concrete wall made in two parts as described of binders which are non-conductors of moisture substantially as described for the purpose set forth.

ELIZUR E. CLARKE.
